UNITED STATES PATENT OFFICE.

EDGAR H. FREEMAN, OF TRENTON, NEW JERSEY.

CAP AND SHELL FASTENING FOR LAMP-SOCKET CASINGS.

1,096,422.

Specification of Letters Patent. Patented May 12, 1914.

Application filed May 17, 1913. Serial No. 768,234.

To all whom it may concern:

Be it known that I, EDGAR H. FREEMAN, a citizen of the United States, residing at Trenton, in the county of Mercer and State 5 of New Jersey, have invented certain new and useful Improvements in Cap and Shell Fastenings for Lamp-Socket Casings, of which the following is a specification.

This invention relates to the subject of 10 metallic casings for electrical lamp sockets, and more particularly to casings of the adjustable type wherein a plurality of locking positions are provided between the shell and cap parts of the casing so as to enable the 15 casing shell to not only be readily and securely united to the cap after the latter has been fitted in place, but also to permit the shell to be so positioned when locked to the cap as to present the switch-key (of a key 20 socket) in a readily accessible and convenient position for manipulation. To this end the present invention contemplates a simple and reliable fastening connection between the shell and cap parts of the lamp socket 25 casing, which admits of practically a universal circular adjustment for the shell so that the same may be locked by the same locking means in any of a number of different positions, while at the same time preserving all of the desirable features of that 30 type of lamp socket casings having what is termed in the trade a "snap fastening."

A further object of the invention is to 35 provide an improved fastening connection between the shell and the cap parts of a casing which dispenses with the necessity of a locking hole or its equivalent to secure the locked parts against rotation in either direction, and against separation, thus greatly 40 simplifying a fastening of this character while at the same time retaining the maximum strength of the casing.

With these and other objects in view, the 45 invention consists in certain novel combinations and arrangements of parts as will more fully appear as the description proceeds, the novel features thereof being pointed out in the appended claims.

For a full understanding of the invention, 50 reference is to be had to the following description and accompanying drawings, in which:

Figure 1 is a perspective view of a lamp socket casing constructed in accordance with

the invention, the cap being shown as separated from and elevated above the body portion of the casing. Fig. 2 is a vertical sectional view through the complete casing showing the position assumed by the parts after one end of the shell has been forced into 60 the cap, but before the shell has been rotated to bring the lugs of the cap under the lateral arms of the bayonet slots of the shell. Fig. 3 is a similar view showing the position assumed by the parts after the shell 65 has been rotated to bring the lugs of the cap beneath the lateral arms of the bayonet slots, the view also showing the fastening latch moved to a locking position at one side of the lug in one of the slots. Figs. 4 and 70 75 5 are similar enlarged detail sectional views, on the line of section indicated by the line $a--a$ in Fig. 1, illustrating the mounting of the slidable fastening latch and also respectively in its idle and locking positions.

Like reference characters designate corresponding parts in the several figures of the drawings.

The improved fastening forming the subject matter of this application may be employed in connection with any approved type of two-part casing for electrical lamp sockets, although for illustrative purposes the invention is shown in the drawings as embodied in a metallic lamp socket casing 80 comprising a metallic shell or body part 1 and a cap part 2, the said cap part being provided with a peripheral flange 3 which telescopically receives an end portion of the shell or body portion 1. 85

The end of the shell 1 which is telescopically engaged by the flanged portion of the cap 2 is formed with a series of equidistant or regularly spaced bayonet positioning slots 4 which open through the end of the 95 shell. The end of the shell may also be formed with a suitable slot or opening 5 to receive the switch key, although this slot may be omitted where the key is not used. The flanged portion of the cap 2 is formed 100 with a series of inside equidistant lugs 6 of the same size, shape, and projection, and which correspond in number and position to the bayonet positioning slots 4 of the shell 1. It will thus be obvious that by inserting 105 the end of the shell or body portion 1 into the cap 2 in such a manner that the lugs 6 will enter the bayonet slots 4, and then ro-

tating the shell or cap to bring the lugs into the lateral arms of the bayonet slots an interlocking connection will be produced which will hold the shell and cap together and prevent the said members from being separated by a direct pull.

According to the present invention, the mouth of one of the bayonet positioning slots 4 is adapted to be covered and uncovered by means of the movable latch designated by the numeral 7 and adapted to be moved into a locking position within the mouth of one of the slots and at one side of the holding lug or projection therein. The movable fastening latch 7 is designed to be suitably supported on one member of the casing, preferably the shell. While the latch may be differently constructed and mounted in different ways without departing from the invention, the same preferably consists of a single strip of thin sheet metal which consists of what may be appropriately termed a slide bolt which is suitably guided for sliding movement on the shell or sleeve part of the casing. Different expedients may be resorted to in order to slidably support the fastening latch on the shell in such a manner that it forms a permanent part of the fixture, but one way of accomplishing this is shown in the drawings and consists in mounting the latch for sliding movement through a guide opening 8 formed in the shell and having one end of the latch forming strip folded or looped as at 9, forming a guiding loop that slidably embraces an edge portion of the shell, thereby securely holding the latch in place while at the same time permitting it to have its necessary movement.

The fastening latch 7 is formed at one end with a finger flange 10 by means of which it may easily be manipulated, and at an intermediate point the latch is formed with a catch projection 11 made by a prick punch or otherwise, which catch projection is adapted to have a snap engagement with a corresponding keeper indentation or recess 12 punched or otherwise formed in the metal of the shell, as may be best seen in Figs. 4 and 5 of the drawings. When the latch is moved to its locking position within the mouth of one of the bayonet slots, the projection 11 snaps or springs into engagement with the recess 12, thereby securely retaining the latch in its said locking position, while at the same time not interfering with it being slid to its retracted position for the purpose of unlocking the shell.

When applying the shell to the cap part of the casing, the fastening latch is retracted to its out-of-the-way position shown in Fig. 1 of the drawings, thereby permitting the slotted end of the shell to be inserted in the cap, as plainly shown in Fig. 2 of the drawings. In this position of parts, each of

the holding lugs 6 engages in one of the bayonet positioning slots. Upon partial rotation of the shell (or of the cap as conditions may sometimes require), the lugs 6 are carried into the lateral portions of the bayonet slots as shown in Fig. 3 of the drawings, whereupon it is simply necessary to slide the latch 7 longitudinally to bring one end thereof into the mouth of one of the positioning slots and at one side and against the shoulder of the particular lug in that slot. In this position of parts, the cap and shell are positively locked against displacement in any direction, either longitudinally, or rotatively in either direction, but to release the parts this may be readily accomplished by retracting the fastening latch, and reversing the operations above described.

Attention may be directed to the fact that with the bayonet positioning slots 4 and the lugs 6 arranged at uniform intervals, the casing may be interlocked with the cap with the key receiving slot 5 on any side thereof, the fineness of the adjustment which is possible depending upon the number of bayonet slots and lugs which are employed. It will be obvious that any desired number of the bayonet positioning slots may be utilized, although for ordinary purposes it has been found that four of these positioning slots answer all practical requirements.

What I claim is:

1. A lamp socket casing including a cap member provided with a lug, a shell provided with a bayonet positioning slot to receive the lug, and a fastening latch consisting of a strip slidably supported on the shell and movable into the mouth of the slot at one side of the lug engaged therein.

2. A lamp socket casing including a cap member provided with a lug, a shell member provided with a bayonet slot to receive the lug, and a fastening latch consisting of a strip slidably supported for a limited movement on the shell and movable into the mouth of the slot at one side of the lug engaged therein, and retaining means for holding the latch in its locking position.

3. A lamp socket casing including a cap member having an interior lug, a shell member having a bayonet slot to receive the lug and a keeper recess, and a fastening latch slidably mounted on the shell for a limited movement to engage at one side of the lug when engaged in the slot, said latch also being provided with a catch projection having a snap engagement with the said recess.

4. A lamp socket casing including a cap member provided with a lug, a shell member provided with a slot to receive the lug, and a guide opening, and a fastening latch slidably mounted for a limited movement in the guide opening of the shell and having a looped end slidably engaging an edge por-

tion of the shell, said latch also having a finger piece and movable into the mouth of said slot at one side of the lug therein.

5. A lamp socket casing including a cap member provided with a plurality of similar equidistant lugs, a shell member provided with a plurality of similar bayonet slots corresponding in number and spacing to the said lugs, and a fastening latch slidably

mounted on the shell for limited movement 10 and movable into and out of the mouth of one of the bayonet slots.

In testimony whereof I hereunto affix my signature in the presence of two witnesses.

EDGAR H. FREEMAN.
